The ornamental design for a shovel head, as shown.

DESCRIPTION

FIG. 1 is a perspective view showing the front of a shovel head embodying the principles of the present invention; FIG. 2 is a rear perspective view showing the rear of the shovel head seen in FIG. 1;

FIG. 3 is a front view of the shovel head seen in FIG. 1; FIG. 4 is a rear view of the shovel head seen in FIG. 1; FIG. 5 is a right side view of the shovel head seen in FIG. 1;

FIG. 6 is a left side view of the shovel head seen in FIG. 1; FIG. 7 is a top view of the shovel head seen in FIG. 1; and, FIG. 8 is a bottom view of the shovel head seen in FIG. 1. In the drawings, the broken lines depict environmental subject matter only and form no part of the claimed design. Shade lines having a combination of long and short lines in the drawings show contour and not surface ornamentation.
